(57) CLAIM

The ornamental design for a packaging, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front plan view of the packaging in a flat unwrapped state showing our new design.

FIG. 2 is a front view thereof shown in a configuration of use of this design.

FIG. 3 is a front plan view of a second embodiment thereof.

FIG. 4 is a front view shown in a configuration of use of a second embodiment thereof.

FIG. 5 is a front plan view of a third embodiment thereof; and,

FIG. 6 is a front view shown in a configuration of use of a third embodiment thereof.
